UNITED STATES PATENT OFFICE.

ALVA S. GROVES AND LESTER P. GROVES, OF REEDSVILLE, WEST VIRGINIA.

RIM AND FELLY CONNECTION.

Application filed March 1, 1923. Serial No. 622,074.

To all whom it may concern:

Be it known that we, ALVA S. GROVES and LESTER P. GROVES, citizens of the United States, residing at Reedsburg, in the county of Preston and State of West Virginia, have invented certain new and useful Improvements in Rim and Felly Connections; and we do hereby declare the following to be a full, clear, and exact description of the invention, such as will enable others skilled in the art to which it appertains to make and use the same.

This invention relates to a rim and felly connection particularly adapted for use with vehicle wheels equipped with pneumatic tires.

It is aimed to provide a novel, inexpensive, efficient and durable construction enabling rapid detachment and replacement of the rim from the wheel, particularly avoiding the manipulation of a plurality of bolts as is at present necessary, and to provide means on the rim and felly adapted to be wedged together by circumferential movement of one of said parts with respect to the other of said parts, and which movement may be imparted through manipulation of means having the required leverage.

A fourth object is to provide a construction wherein means is operable to circumferentially move them relatively to the felly or vice versa to disalign or interengage the means of the rim and felly to be so that the former may be removed more expeditiously by lateral movement.

It is also aimed to provide a novel toggle joint means for any mechanism to attain the result mentioned.

Additional objects and advantages will become apparent from a consideration of the description following taken in connection with accompanying drawings illustrating an operative embodiment.

In said drawings:—

Figure 1 is a view in side elevation illustrating an automobile wheel or other wheel embodying our improvements;

Figure 2 is a view similar to Figure 1 showing the felly and rim assembled but unlocked;

Figure 3 is an edge view of a fragmentary portion of the felly illustrating the toggle mechanism;

Figure 4 is a detail perspective view of the toggle mechanism on an enlarged scale;

Figure 5 is a perspective view of a fragmentary portion of the rim;

Figure 6 is a view in side elevation of a fragmentary portion of the wheel and rim, portions of the felly and rim being in vertical section to illustrate the toggle mechanism;

Figure 7 is a sectional view taken on the plane indicated by the line 7—7 of Figure 6;

Figure 8 is a sectional view taken on the plane indicated by the line 8—8 of Figure 1, and

Figure 9 is a sectional view taken on the plane indicated by the line 9—9 of Figure 2.

Like reference characters designate like or similar parts in the different views.

In reducing the invention to practice, a conventional wheel is shown at A being provided with a felly B. This wheel is representative of that type used on automobiles, motorcycles and the like, and which are usually equipped with pneumatic tires (not shown) carried by a demountable rim C.

At suitable intervals about the periphery of felly B, projections 10 are fastened in any suitable manner. These projections are of wedge shape or provided with inclined outer surfaces as shown. They also have central circumferentially extending slots 11.

Extending inwardly from rim C, at the same intervals as projections 10, and preferably integral with the rim, are lugs or projections 12 having their inner surfaces inclined so that they will be wedge shaped like the projections 10. In addition, integral with the projections 12, ribs 13 are provided, disposed centrally of the projections 12 and adapted for entrance into the slots 11.

With the construction described, the rim may be applied to the felly B or removed therefrom, by lateral movement when the lugs or projections 10 and 12 are laterally disaligned, as suggested in Figure 2. Also when in that position, the rim C may be moved circumferentially with respect to the felly B so that said projections 10 and 12 will engage or move together, as illustrated in Figure 3. It will be realized that the ribs 13 are received in slots 11 so as to rigidify or brace the structure against relative lateral strain of the rim or felly.

A suitable means is provided to effect the circumferential movement of the rim referred to. To this end a rocker shaft 14 is journaled transversely of the rim C. This

2

rocker shaft may be square or have any other wrench engaging head, extending outwardly beyond one side of rim C and it also has a crank or offset 16 disposed within a recess 17 located in rim C. The end of shaft 14 adjacent head 15 is preferably directly journaled in a bearing plate 18 fastened at 19 to the felly. An inwardly extending slot 20 in said rim facilitates the assembling or 10 positioning of said shaft. Pivoted to the crank 16 is a link 21 which is disposed in the recess 17. Screw threaded or otherwise adjustably mounted on link 21 for longitudinal movement is a sleeve 22 preferably of spool shape as shown so as to have flanges 23 integral therewith and in spaced relation. A leaf spring 24 is fastened to the rim C and at 15 its free end contacts with the link 21 and normally maintains the crank 16 and link 21 alined and within the recess 17.

An abutment block 16^a is fastened to felly B within recess 17 in order to resist movement of the toggle joint at its pivot toward the hub of the wheel past locked position. 25 Also to resist any tendency of the toggle to unlock the rim as the latter travels on the ground, the crank 16 and link 21 in locked position are disposed in slight convergence toward the hub of the wheel.

30 A bifurcated abutment or fork 25 extends inwardly from the rim C and is adapted to detachably straddle the sleeve 22 intermediate the flanges 23. Lateral movement of the rim accompanied by a slight tilting movement enables the fork 25 to be engaged with the sleeve 22 when crank 16 and link 21 are alined and the lugs or projections 10 and 12 are disaligned.

35 A suitable wrench or tool is adapted for engagement with the head 15 so that when the parts are in the position shown in Figure 2, the wrench will be turned in order to turn the shaft 14 in the direction of the arrow to the extent of one hundred and eighty degrees which through its connection with the link 21 as a toggle moves the rim C in the direction of the arrow causing engagement of the lugs 10 and 12 in wedge fashion with the ribs 13 disposed in the slots 11. 45

50 In order to accommodate the toggle movement of the crank 16 and link 21, the inner surface of the rim C is cutaway or recessed

to provide clearance as at 26. The crank and link automatically lock in their different positions in view of the provision of the 50 spring 24.

In order to remove the rim C, the shaft 14 by means of a wrench or other tool is moved one hundred and eighty degrees in the direction opposite to that described 55 which in turn moves the rim C in the direction opposite to that indicated by the arrows to dispose the same in the position of Figure 2 where it may be readily removed or replaced in the manner described.

60 Particular attention is called to the fact that due to the threaded or adjustable connection of the sleeve 22 on link 21, the extent of movement or throw of the rim circumferentially with respect to the felly B 65 may be varied in order to compensate for wear and at all times to insure intimate wedge engagement of the projections 10 and 12.

65 As merely one operative embodiment has 70 been illustrated and described, it is to be understood that changes in the details may be resorted to provided they fall within the spirit and scope of the invention.

75 We claim as our invention:—

80 A demountable rim member and felly member connection having securing means interengageable by circumferential movement with respect to the other member, a crank having an operating shaft journaled 85 on one of the members, a link pivoted to said crank, a sleeve screw threaded on said link, said sleeve having flanges, the last mentioned member having a recess accommodating said crank, link and sleeve, a 90 spring on the last member overlapping the crank normally maintaining the crank and link in alinement, the other member having a fork to engage said sleeve intermediate 95 said flanges, and said shaft being operable to impart said circumferential movement.

95 In testimony whereof we affix our signatures in presence of two witnesses.

ALVA S. GROVES.
LESTER P. GROVES.
